UNITED STATES PATENT OFFICE.

WILLIAM T. VAN DORN, OF LINCOLN, NEBRASKA.

CAR-COUPING.

SPECIFICATION forming part of Letters Patent No. 271,553, dated January 30, 1883.

Application filed November 28, 1882. (No model.)

To all whom it may concern:

Be it known that I, WILLIAM T. VAN DORN, of Lincoln, in the county of Lancaster and State of Nebraska, have invented a new and useful Improvement in Car-Couplings, of which the following is a full, clear, and exact description, reference being had to the annexed drawings, forming part of this specification.

This invention relates to an improvement upon the car-coupling shown and described in Letters Patent No. 258,160, granted to me under date of May 16, 1882.

The invention consists of an improvement in the coupling-bar, whereby the latter is adapted for coupling with cars using the ordinary pin-and-link coupling, and also in the retaining device for holding the catch of the coupling-bar in engagement with the pin.

In the drawings, Figure 1 is a horizontal section of the draw-head embodying my improvement; and Fig. 2 is a vertical section of the same, showing the adjustment of the coupling-bar for coupling with ordinary couplings.

The coupling-bar *b* is provided with a catch, *c*, at one end, and a perforation, *g*, by which the opposite end is to be coupled with a draw-head. This opposite end *d* is made heavy, and extends beyond the perforation *g* from the catch *c*, in order that when said end is coupled with a draw-head the bar will be held in a horizontal position for automatic coupling at the catch end with another draw-head. Now, to adapt this coupling-bar for coupling with the ordinary pin-and-link coupling, which is used on many cars, I provide the heavy end *d* of the bar *b* with a slot, *e*, extending from its end nearly to the perforation *g*, thus forming a combined link and catch-bar. For coupling with cars having my coupling one of the cars is to be coupled with the bar *b* by means of the perforation *g*, as in my former inven-

tion above referred to, and the catch *c* on the opposite end of the bar is to be coupled automatically with another car having a bevel coupling-pin, *f*, behind which the catch is to be forced. When it is desired to attach a car having the pin-and-link coupling the pin *f* is to be withdrawn, and the bar *b* is to be inserted into the draw-head until the pin *f* may be inserted through the perforations *g i*, as shown in Fig. 2. The link portion *d* of the bar *b* may then be coupled with an ordinary pin.

The improved retaining device consists of the bar of wrought-iron *h*, which is pivoted on a vertical bolt, *h'*, in the opening *a* in the side of the draw-head, and the coil-spring *l*, set in recesses *m*, formed respectively in the bar *h* and the opposite wall of the draw-head. The bar *h* is beveled at its rear end, and its bevel rests against the corresponding bevel of the wall *j*, which latter serves as a stop for the bar *h* against the action of spring *l*. The forward end of the bar *h* is pressed inward against the coupling-bar *b* to hold the catch *c* in engagement with the pin *f*.

In Fig. 1, *i* indicates the additional coupling-pin above referred to, which is used as a safety-pin to hold the bar *h* from yielding to the pressure of the coupling-bar when not used for coupling.

What I claim as new is—

The combination, with the coupling-bar having catch *c* and the draw-head having a bevel coupling-pin, of the bar *h*, pivoted in opening *a* and forming one side of the draw-head, and the coil-spring *l*, set in recesses *m*, substantially as shown and described.

W. T. VAN DORN.
